ELECTRONIC TELEPHONE ANSWERING UNIT

Francis A. Foresta, Paramount, Calif., assignor to T.A.D. Avanti, Inc., Paramount, Calif.

Filed July 29, 1971, Ser. No. 167,561

Term of patent 14 years

Int. Cl. D14—03

U.S. Cl. D26—14 A

FIG. 1 is a front perspective view of an electronic answering unit showing my new design.

FIG. 2 is a rear elevation of the unit;

FIG. 3 is a side elevation, both sides of the unit being identical; and

FIG. 4 is a bottom plan view of the unit.

I claim:

The ornamental design for an electronic telephone answering unit, substantially as shown and described.
